AUTOMATIC HEALD STOP MOTION FOR
DOBBY LOOMS

Paul Riesch, Turbenthal, Switzerland

Application February 4, 1948, Serial No. 6,246
In Switzerland November 28, 1947

9 Claims. (Cl. 139—364)

1

Mechanical or electrical warp stop motions with or without droppers, brought forward hitherto within a rather long period of time, could as a rule not stand the test of practice on account of their limited possibilities of application and intricate design. The adoption of known warp stop motions has been possible only for quite limited kind of weaving. Thus, for instance, in wool, jute and linen weaving no material progress has been made in the design of the usual warp stop motions.

Now the object of the present invention is a mechanical or automatic heald stop motion for dobby looms which is distinguished from known warp stop motions in that on each heald frame two racks with upper teeth are placed in parallel which pass with play through all the heald eyes, one rack being mounted firmly in the frame, whilst the other—movable in longitudinal direction with respect to the stationary one—is at one end in driving connection with a lever pivotally supported on the heald frame, a stop device rigidly mounted on the loom frame projecting into the motion path of said lever, whereby at the side of the heald frames opposite the abutment a cantilever common to all heald frames is oscillatably arranged on an axis rigidly secured to the loom framing, which cantilever projects into the vertical motion path of the movable rack retained in one extreme limit position and is operatively connected to the stop motion of the loom.

The accompanying drawing illustrates by way of example a preferred form of embodiment incorporating the invention.

Fig. 1 shows an elevation of the left-hand half of a heald frame;

Fig. 1a represents an elevation of the right-hand half of the heald frame with the stop motion of the loom;

Fig. 2 is a vertical section taken on the line 2—2 of Fig. 1a;

Fig. 3 is a sectional view taken on the line 3—3 of Fig. 1;

Figs. 4, 5 and 6 show various details.

Referring to said annexed drawing, the heald frame 1 preferably comprises horizontal wooden and vertical metallic parts, stirrups 2 being arranged on the former, from which start the cords or belts used for raising and lowering the heald frames (harness) vertically guided between laths 3, 4 of the loom. Disposed on top within the frame area of the heald frames are two horizontal racks 5, 6 and at the bottom ordinary bar 7 adapted to arrange and or to suspend the healds

2

8, through the eyes 9 of which the warps 10 are passed in the usual way to form the shed.

The rack 5 and bar 7 are supported in bearings 11 (Figs. 1 and 2) on the vertical parts of the frame, each of them being secured in place by a resilient pin 12 which engages covering holes of the bearing and the bar. The rack 5 has bush 13 and is of channeled cross-section and receives in its hollow space the flat rack 6 as more particularly shown in Fig. 3, the rack 6 having prismatic teeth 14 substantially of identical height and length. Further, the rack 6 is disposed for end-wise movement in rack 5. Now, another arrangement is such that with moving heald frame the rack 6 is displaced in one direction and then reset by spring action. To ensure this movement in a continuous way, the rack 5 is provided with spaced holes 50 through which the dust which may accumulate thereon is eliminated.

In the form of embodiment shown, the displacement of the rack 6 with lowering heald frame takes place by a stop. For this purpose the rack 6 is at one end brought into operative engagement with crank lever 15 pivotally mounted at 16 on the heald frame, embracing by its fork a pin 17 of the rack 6, which pin enters an elongated slot 18 of rack 5. A spring member 19 restores the moved rack 6 to normal. The bell crank levers 15 on the heald frames cooperate with stops situated on the loom wall.

Figs. 1 and 5 exhibit, with a small number of heald frames, a commonly employed stop plate 20 which extends in the direction of the warp, having a sloped contact edge 21 conforming in shape with the shed. Said plate is secured by an angle piece 23 to the guide bar 3 firmly seated on the loom board 22, being adjustable to any direction, especially vertically and horizontally, by means of the slots 24 and 25.

With an increased number of heald frames, the stop plate will be replaced by spaced stops 26 which in number correspond to that of the heald frames, each of them being (individually) adjustable in height on the horizontally displaceable angle piece 23, through slot 27. Thus, with single manipulation, this arrangement allows of easily obtaining an absolutely uniform shedding.

The action of the aforescribed device is as follows:

If, with the loom in operation, the heald frames form the shed, then, with lowering shafts, the arm 15' of the related bell crank lever 15 strikes against the plate 20 or one of the stops 26, thus causing the rack 6 disposed in the stationary rack 5 to move to the right in the direction of

the arrow 28, i. e. by more than one tooth pitch, whilst with rising of the heald frames it is restored to normal by the action of spring 19. In the shedding the healds 8 are held in the raised position I (Figs. 1 and 3) by the tensioned warp threads of the lower shed so that the movement of the rack 6 remains without influence on the healds. However, the healds pertinent to the broken warp threads are not kept raised, but fall by their own weight until their eyes 29 lie on the racks 5, 6 so that these healds are raised by the teeth of rack 6 moving to the right, where they finally drop into a space between the teeth of the stationary rack 5 (see position II in Fig. 1). At the start of the return of rack 6, one or more heald eyes 29 become clamped between two teeth of the racks 5, 6 as in Fig. 6. To ensure this action the eye 29 is provided with a horizontal straight end portion 29'. When using a hooked heald the plate forming the eye will be of similar design.

Due to this engagement the rack 6 cannot return to normal, but projects at 30 at the right end, somewhat beyond the heald frame. This incident is utilized for stopping the loom. An example of an arrangement adapted therefor is as follows:

Supported by a straight heald frame guiding bar 4 (attached to the loom) is an upstanding arm 31 which at its head pivotally carries a lever arm 33 on axis 32 and in addition a rigidly mounted arm 34, a resilient carrier pin 35 being provided therebetween to interconnect the said two arms. At one end the loose arm 33 carries a bar-like cantilever 36 which extends closely at the side of the heald frames arranged in tandem so that the projecting end 30 of the rack 6 of all heald frames acts upon the common cantilever 36. Further, fixed on pivot axis 32 is a lever arm 37 connected through a Bowden wire 38 to the actual stop motion.

According to the illustrated form of embodiment, the stop motion includes the well-known link-motion starting lever 39 pivotally supporting a double lever 40 weighted at 41. The weight 41 is normally retained by a pawl 42 in its raised position, in which the lever 40 is so positioned as to render ineffective a projection 43 on the slay with respect thereto. The Bowden wire 38 leads to the said pawl 42. If upon lift of one or more heald frames the cantilever 36 is carried by the aforementioned rack ends 30, the lever arm 37 is caused to oscillate upwardly in the direction of the arrow, thus tensioning the Bowden wire 38 to release the pawl 42. The falling weight causes a pivotal movement of lever 40 which incidentally enters the range of the projection 43 which upon action of the slay strikes against lever 40 to disengage the starting lever 39 in known manner from a link notch, which then is brought to the "off" position by spring action. Thus the loom is automatically stopped. A compression spring 44 restores pawl 42 and lever arm 37 to normal, an adjustable stop which, for instance, includes a bolt 51 and a contact plate 52, keeping the Bowden wire taut.

Incidental to the stoppage of the loom an indicator or signalling attachment is operated calling the weaver's attention to the action of this warp stop motion. The arrangement as an exemplified form of embodiment according to Figs. 1 and 2 is such that a driver or carrier 45 provided on lever arm 37 causes movement of a lever arm 46 having a conspicuously coloured pointer 47 hinged thereto. When acted upon, the pointer

projects from a casing into an easily seen position in which it is retained by a shoulder 48.

It is further advantageous to substantially or exactly balance the lever arm 33, 34 and the cantilever 36 as by means of a weight 49 in order to smooth in so-to-say feeler-fashion, the knock of the rack end 30 on the cantilever 36.

With stopped loom, even with a large number of heald frames the weaver can easily locate any failure of the warp thread. The indicator or signalling attachment 46, 47 indicates above all that the stoppage of the loom is due to the action of the warp stop-motion and not of the weft one. Moreover, the end 30 of the rack 6 projecting laterally of the heald frames (one or more) makes it clear at which heald frame a warp has failed, and by the movement of the related rack through the lever arm 15' the location of the thread breakage can be made visible, because the lowered heald hangs there in the teeth of the two racks.

To ensure reliable operation it is necessary to determine the healds according to the count of yarn.

The advantages of the aforescribed warp stop-motion over the existing types are:

1. Optimum simplicity and possibility of adaptation; device usable for all kinds of fabrics.

2. Droppers are dispensed with, which means fewer thread breakages. Suppression of cost for positioning and drawing-in droppers, consequently also easy passage of the warps.

3. No loss of time in connection with locating thread breakage, as the failure is shown in the related heald frame. Poorly sized material cannot impair the stop-motion, since the warp threads are not directly connected to the actual mechanism.

4. Simple supervision for the weaver, since the arrangement includes but a few suitably assembled parts. It can be mounted on all types of looms by the weaving master himself, after brief instructions.

The trend of opinions gathered by practical experience is that due to its special economic properties the arrangement under review will become introduced within a few years in the whole textile industry for all kinds of fabrics, particularly plain ware.

50. What I claim is:

1. In an automatic heald stop-motion for dobby looms, vertically movable heald frames, two racks with upper teeth arranged in parallel in each frame and passing with play through all the heald eyes, one rack being stationary in the related frame and the other rack being mounted for endwise movement relative to the stationary rack, a lever pivoted on each frame and connected with the related movable rack, a stop device engageable by each lever moving with the frame to actuate said lever and the movable rack, a cantilever common to the several frames and projecting into the path of the movable rack moving vertically with the frame and retained in the position assumed when actuated by said lever, said cantilever being connected to the stop motion of the loom.

2. An automatic heald stop-motion for dobby looms as claimed in claim 1, wherein the rack stationary in the heald frame is of channeled cross-section, its hollow space receiving the movable rack, said stationary rack being provided with perforations through which the accumulated dust can escape.

70. 3. An automatic heald stop-motion for dobby

looms as per claim 1, wherein the stop device includes a plate adjustable to any direction.

4. An automatic heald stop-motion as claimed in claim 1, wherein for looms with an especially large number of heald frames, the stop device includes for each frame a special individually adjustable stop.

5. An automatic heald stop-motion as claimed in claim 1, wherein the stop motion includes a pawl operatively connected through a Bowden wire to a lever which carries the cantilever, said pawl reaching in its one released position the path of the slay, on the action of which the starting lever is returned to its "off" position.

6. An automatic heald stop-motion as claimed in claim 1, having a movable member of the stop motion in operative connection with a signalling attachment, a lever arm which loosely pivots on an axis being connectable to an arm rigidly mounted on the latter.

7. An automatic heald stop-motion as claimed in claim 1, wherein each of the healds or hook

10

15

20

healds has an eye with a straight horizontal upper web.

8. An automatic heald stop-motion as claimed in claim 1, wherein the racks are supported by bearings laterally on the heald frames, being secured thereto by resilient pins.

9. An automatic heald stop-motion as claimed in claim 1, wherein the cantilever and the lever carrying it are counterweighted.
